UNITED STATES PATENT OFFICE.

ORVILLE C. MANN, OF OAK PARK, ILLINOIS.

RAILWAY-GRADING MACHINE.

No. 853,928.

Specification of Letters Patent.

Patented May 14, 1907.

Application filed December 29, 1906. Serial No. 349,982.

To all whom it may concern:

Be it known that I, ORVILLE C. MANN, a citizen of the United States, residing at Oak Park, in the county of Cook and State of Illinois, have invented new and useful Improvements in Railway - Grading Machines, of which the following is a specification, reference being had to the accompanying drawings, forming a part thereof.

10 The purpose of this invention is to provide an improved apparatus for use in railway grading, with particular reference to spreading and leveling the spoil or excavated material at the sides of the track.

15 It consists in means for supporting and adjusting the spreaders to cause them to level the surface whether they are adjusted at high or low position, and in the means for operating the lateral spreaders both in adjusting the 20 height and in folding them up out of operative position and causing them to operate the forward spreaders.

25 It also consists in certain details of specific construction, as may be understood from the following specifications and claims.

In the drawings:—Figure 1 is a plan view of a railway grader embodying this invention showing the spreading device upon one side only. Fig. 2 is a side elevation of the same. 30 Fig. 3 is a side elevation of the same showing the spreaders folded back out of operative position. Fig. 4 is a rear elevation of the same with the spreaders in full line in low operative position, as in Figs. 1 and 2, and in dotted line in elevated operative position, and also in position folded back out of operation. Fig. 5 is a partly sectional view, section being made at the plane of the line 5—5 on Fig. 1. Fig. 6 is a section at the line 6—6 on Fig. 1, 35 but showing the lateral spreader in the position in which it appears in dotted line in Fig. 4. Fig. 7 is a transverse section similar to Fig. 5, but showing a modified construction of the means for raising, lowering and guiding the lateral spreader. Fig. 8 is a partly sectional elevation from the inside looking outward toward one of the lateral spreaders, section being made longitudinally of the car at line 8—8 on Fig. 1. Fig. 9 is a detail view, 40 partly sectional, of the device for taking up slack on the operating cable, section being made longitudinally of the notched flange for engagement with the detent dog, and axially through the guide-bearing of the take-up spindle. Fig. 10 is a section at the line 10—10 on Fig. 9. Fig. 11 is a detail plan view of

the take-up device for the lifting cable. Fig. 12 is a section at the line 12—12 on Fig. 11.

The grading apparatus herein described comprises a flat car whose frame or platform 60 is represented at A, and on which there are mounted motors and power connections for operating the wings hereinafter described, which have the function of spreading and leveling the excavated material alongside 65 the track. For the purpose of supporting the drums and pulleys over which the cables pass for operating the wings and affording convenient space for the motors and connections, there is provided on the car platform 70 a frame structure consisting of upright posts or standards, 1 and 2, which are located at a distance from the opposite ends of said platform, and are braced by slant posts, 3, both longitudinally and transversely of the car; 75 and intermediate these braced posts at a position somewhat nearer the forward one of them there is mounted on the car platform a pyramidal standard or tower comprising four slant posts, 35, 35, 35, 35, which are connected at their upper ends and surmounted by a pulley-bearing frame, 4. The slant bars of these several frame structures are connected by horizontal frame bars, 7, binding them all together in a rigid structure for supporting the various shafts and other parts of 80 the mechanism for operating the wings, as hereinafter described. In the pulley-bearing frame, 4, there are journaled sheave pulleys, 5, 5, about which cables, 6, 6, extend 85 for connection with the lateral spreading and leveling wings hereinafter described, said cables being designed for folding up said wings out of operative position. On the posts, 1 and 2, bearings are mounted for a 90 horizontal shaft, 8, extending longitudinally of the car, having on it sheave pulleys, 9, 9, for cables, 10, 10, which are wound about said sheave pulleys, as more particularly 95 hereinafter described, for adjusting up and down the lateral spreading and leveling wings.

In the drawings there are shown only the wings upon one side of the car, those upon the opposite side being identical in construction and mode of operation. At the forward end of the car wings for spreading and leveling the excavated material are suspended so as to extend across the rails respectively, one only of said wings being shown upon one side of the car. This wing, 15, is adjustable vertically on the suspending arms, 16, which take

through slide boxes, 17, 17, on the inner or back side of the wing, the arms, 16, having pin holes at intervals in their length through which pins, 16^a, may be inserted above and below the slide boxes to secure the wings at any height to which they may be adjusted from the lowest position at which the lower edge of the wing rests upon and extends across the top of the rail, to any higher position desired. A flanged wheel, 15^a, on the wing, 15, may be arranged to travel on the rail. The arms, 16, extend from a shaft, 18, mounted on the forward end of the platform, and the entire spreading wing, 15, may be folded back about said shaft out of operative position, leaning then back inward against the inclined brace, 3, of the forward post, 1, and against the similarly inclined brace of the tripod frame consisting of the three mutually bracing posts, 2^a, 2^a, 2^a, mounted at the forward end of the platform. The purpose of these spreading wings, 15, is to sweep the earth from off the top of the rail and thence outward, clearing a strip parallel with the rail extending a short distance outside the same, preparatory to the action of the main lateral spreader, 20, which extends divergently rearward from a point at which it laps inside of the rear end of the spreader wing, 15, to about the middle of the length of the car, or as far as it may be considered practical or necessary to extend it in order to give it the desired breadth of sweep. In the form shown in all the figures except Fig. 7 the lateral wings, 20, (one only being shown) are carried by a rigid frame structure consisting of arms, 21, 21, 21, braced by brace bars, 22, 22 and 23, so as to carry said spreader, 20, rigidly at the ends of said arms. These arms, 21, at their inner ends are guided for substantially vertical movement. In the same vertical planes with the arms, 21, and rigid therewith respectively, are struts, 24, which diverge downwardly from the arms for bearing against suitable guides which are provided for them on the side of the car, the spread of the arms, 21, and struts, 24, constituting a broad base extending vertically for holding the wing in fixed position offset from the side of the car when the inner ends of the arms and struts are stopped and held by any means fixedly with respect to the side of the car.

The preferred form of means for holding and guiding the arms, 21, is illustrated in all the figures except Fig. 7, consisting in pivotally connecting said arms at their said inner ends with links, 26, which extend from their connection with said arms, 21, back above the car and are fulcrumed on the latter. By swinging the links, 26, about their fulcrums on the car it will be seen that the pivotal connection of the links to the inner ends of the arms, 21, may be carried, in an arc whose chord is substantially vertical,

through a considerable vertical distance. The drawings show the parts proportioned for thus swinging the links to carry their outer ends vertically a distance of about three feet. It will be seen that if the inner ends of the struts, 24, are made to follow arcs struck with a radius equal to the length of the links, 26, about centers distant from the fulcrums of said links as far as the feet of the struts are distant from the inner ends of the arms, 21; the resulting movement of the wing will be the same as if it were carried by parallel links. It is not practicable to provide such parallel links, but instead I provide pockets or guide-ways for the inner ends or feet of the struts which are curved in the path which the lower members of such parallel links would take if they were so provided,—that is, in arcs struck with a radius equal to the length of the links, 26, about centers spaced below the fulcrums of the links a distance equal to the spread of the arms, 21, and struts, 24,—that is, a distance between the connection of the pivotal arm, 21, to its link, 26, and the foot of the strut. By this means the wing is caused to preserve its outer face vertical throughout its whole range of adjustment effected by swinging the links, 26. The links, 26, which carry the several arms, 21, being of the same length, the wing is lifted an equal distance at all points of its length, and being mounted so that its lower edge is horizontal at one position, it is kept horizontal at all positions throughout the range of its adjustment, notwithstanding it has the necessary divergence rearward to spread the material and is operated pivotally for raising and lowering,—a construction which, it will be noticed, would cause the lower edge to become inclined from horizontal position, and to change its inclination steadily throughout the swinging movement, if such movement were effected merely by swinging about a single pivot.

The lateral spreading and leveling wings are designed to be folded back above the car so as to stand substantially within the vertical side lines of the car when out of use; and it is for this purpose primarily that these wings are pivoted to their support, which, in the construction above described, consists of the links, 26. For folding the wings thus back out of use above the car, the cables, 6, above mentioned extend from the sheave pulleys, 5, one to each of the spreading wings, being connected thereto about one-third of the way back from the forward end of the wing and at the upper edge thereof at a staple, 30. In order to obtain a desirable direction of pull for lifting the wing by means of the cable without mounting the sheaves, 5, at an impracticable height above the car, each pulley is provided with an outrigger, 31, fulcrumed on the frame structure at any convenient point,

and of such length that the cable, 6, passing over it may extend almost vertically down to the staple, 30. When the wing is folded back out of use it rests against the post, 2, at the forward point, and at the rear point against a post, 11, which is stepped on the angle of the angle-iron horizontal bar, 7, and braced from the opposite post, 11. For starting the wings outward when they are to be swung to working position there are mounted on the forward side of the post—being directly supported on the slant post, 3,—cylinders, 12, 12, whose pistons have thrust rods, 13, which push against the wings respectively when the cylinders are connected with the motive fluid (compressed air) for operating the pistons. At this position the links are nearly vertical, and the outrigger is kept in connection with the cable by any convenient loop or eye provided for that purpose at the end of the outrigger. For lifting and letting down the wings, cylinders, 60, are supplied with compressed air or other fluid for operating their pistons, whose rods, 61, have each a pulley, 62, engaging a loop of the cable, 6, between its end which is secured to a fixed staple, 63, and the guide pulley, 64, from which the cable runs up to the sheave pulley, 9. The amount of cable drawn with this construction, it will be seen, is double the length of the piston stroke.

For raising and lowering the lateral wings to adjust them to the level at which it is desired to have them spread the excavated material, they are connected by the cables, 10, above mentioned, with the sheave pulleys, 9, two such sheave pulleys being mounted on the shaft, 8, and two cables being provided extending from two of the links, 26, to said sheave pulleys respectively. The cables from the two wings run in opposite directions about the sheave pulleys, being secured thereto. When both wings are at the lowest position the cables from both are without slack and extend about the sheaves from the points at which they become tangent therewith at the upper side at opposite sides of a vertical axial plane, thence around in opposite directions to the lower side, each being wrapped a total distance of about 225 degrees on the sheave. It will be seen that the two cables may thus be made continuous, such continuous cable being stapled to the sheave pulley at the lower side, as above stated. With this construction it will be seen that the rotation of the shaft, 8, in one direction will lift one of the wings, and its rotation in the opposite direction will lift the other wing. For thus rotating the shaft, 8, I provide two cylinders, 40, 40, mounted longitudinally on the car, each of the pistons, 41, which operate therein having mounted upon it a pulley, 42. For each wing a cable, 45, is attached at one end to an eye, 43, fixed on the car platform or

framework, and extends thence around the pulley, 42, at that side; thence around a take-up pulley, 44, mounted as hereinafter described; thence up about a guide pulley, 53, to a sheave, 46, on the shaft, 8, being secured 70 to the sheave about which it is wrapped in direction for rotating the shaft by unwinding in direction to wind up the cable, 10, on the same side.

The cylinders, 40, are designed to be connected with any suitable source of fluid for operating them, as compressed air, the connection and source of supply not being shown. When the wings are at their lowest position and the pistons are at their extreme outward 80 position in their respective cylinders,—that is, at a position having their full capacity for working stroke,—either cylinder being connected with the motive fluid, its piston will be driven inward and the wing connected 85 with it will be lifted by swinging links about their fulcrums and in the slots of their guide posts, 27, the struts meanwhile following the curved pockets against which they bear at the lower ends. When either wing, being 90 thus operated, is elevated to desired height it will be secured by pins, 28, 28, set through the guide post, 27, above and below the links, 26. Having lifted one wing in this manner, if it is desired to lift the opposite wing the 95 other cylinder may be similarly connected with the motive fluid and a similar operation performed upon it. In such action of either cylinder it is desirable to avoid acting on the piston of the other cylinder, because it is desirable to be able to operate either wing either up or down at any time, regardless of the position of the other wing and without releasing or discharging the motive fluid from the other cylinder, if said other piston is at that time at 100 the end of a working stroke, the cylinder being filled with compressed air. There must therefore, be a provision for slack in each of the cables, 45, so that when either cable is wound on the sheave for operating its wing, 110 the other cable may yield this slack. But the necessity for taking up, by subsequent travel of the piston, the slack thus yielded should also be avoided, since this would entail large waste of the operating fluid, as well 115 as excessive length of cylinder. Such doubling of the requirement of compressed air or other fluid beyond the amount actually necessary for the work of lifting the wings is effected by providing the take-up pulleys, 44, each mounted in a carriage, 49, sliding in a slotted guide plate, 51, mounted on the car body, a spring, 52, being provided reacting on such carriage and put under tension by drawing out the pulley, 44, toward the pulley, 42, the 120 spring reacting, therefore, with a tendency to retract the carriage, 49, and pulley, 44.

The length of the cables, 45, is such that when the wings are both at their lowest position and the pistons in both cylinders are at 130

the extreme outward position,—with capacity for full working stroke inward,—the pulleys, 44, are drawn out toward the pulley, 42, such distance that upon either of said pulleys being retracted by its spring, it would cause the sheave, 9, to rotate enough to draw the length of the corresponding cable, 10, which would be drawn in lifting the corresponding wing from lowest to highest position. By providing for each cable, 45, a guide pulley, 53, which it passes to reach the pulley, 44, when the latter is at its extreme position toward the cylinder, the movement of the pulley, 44, for taking up this length of cable, it will be seen, is made only one-half said length. With this construction the weight of each wing holds the spring, 52, pertaining to the take-up pulley for such wing, tensioned to the maximum, and the pulley, 44, drawn out toward the cylinder to the maximum extent; and when either piston is operated for lifting the wing which it controls, the cable, 45, at the opposite side is yielded by the yielding of its take-up pulley, 44, toward the pulley, 42, at that side, provided the pulley, 44, connected with the operating piston is prevented from yielding. The stem of the carriage, 49, carries a ratchet dog, 50, which engages a notched flange or ratchet, 54, on the plate, 51, to prevent the carriage from yielding, such dog being disengaged at the side at which the pulley should yield, as above indicated, and left in engagement at the other side. If it is desired to lift the other wing while the first lifted wing remains elevated, said first lifted wing being supported by the pins, 28, in the guide post, 27, the dog, 50, is disengaged from the ratchet flange, leaving the pulley carriage, 54, free to be drawn out against the resistance of its spring. The operating fluid being connected with the cylinder at said other side, the action above described is duplicated at that side, the slack required from the cable, 45, at the side at which the wing is already lifted being yielded by the pulley, 44, advancing to the pulley, 42.

It will be noticed that in the absence of any provision to the contrary, the rotation of the sheave pulley, 9, in the direction caused by the movement for lifting the first operated wing would slack the cable, 10, extending to the other wing by an amount equal to the length of the cable, 10, upon the other side taken up by the sheave, and that it will therefore be necessary, when the other wing comes to be lifted, to rotate the sheave first a sufficient amount to take up this slack before the wing would be lifted at all. And this double amount of rotation of the sheave would in like manner throw slack into the other cable, and double amount of rotation, therefore, would be necessary in each direction, imposing like double movement upon the means for drawing the cable, 45, to ro-

tate the shaft, 8. To avoid this result, the cable, 10, at each side passes intermediate the pulley, 9, and the attachment of the cable to the link by which the wing is lifted, over a guide pulley, 27^a, mounted on the link, 70 and thence about a guide pulley, 28^a, mounted on a spring-retracted carriage, 30^a, which is mounted on the link, the spring, 31^a, for retracting it being put under tension by the weight of the wing so that the cable extends 75 in a straight line past the guide pulley, 27^a, and the take-up pulley, 28^a, when the wing is lowered. When either wing is lifted, slackening or tending to slack the opposite cable, 10, such slack is at once taken up by 80 the take-up pulley, 28^a, the spring, 31^a, retracting said pulley and its carriage for that purpose. The carriage may have a guide stem, 29, at one side of the link pivot and a ratchet stem, 32, at the other side, both 85 guided in suitably apertured lugs projecting from the link pivot bearing. The ratchet stem being engaged by a detent dog, 33, to retain the slack taken up by the reaction of the spring, this dog will be released by the operator when the opposite wing is to be lowered.

In operating the wings it will be found that upon attempting to release the take-up detent dogs for the cables, 45, and for the cables, 10, those dogs will be found under stress of the tension of the cables due to the weight of the lifted wing. And it will be observed that if it were possible to force the dogs out of engagement with their ratchets, the reaction of the strained cable thus suddenly from its condition of tension would shoot the take-up pulley carriage out to the limit of its travel and perhaps dislodge or kink the cable. To avoid both the difficulty of disengaging 101 the dog and the inconvenience of the sudden reaction of the cable, each of the dogs are provided with pivots or journal bearings 10 which are eccentrically mounted on their supports, the eccentric device being provided 11 with a handle or lever arm for rocking it to yield the pivot of the dog in the direction of the stress before the dog is disengaged from the ratchet, the carriage being thereby yielded also in the same direction and the eccentricity being sufficient to cause such yielding to relax the tension of the cable upon the dog before it is disengaged from the ratchet. The eccentric and dog may have co-operating abutments which become engaged after the eccentric has been given the necessary throw to relax the cable, the same movement being then continued after the abutments are encountered to lift the dog.

In Figs. 9 and 10 the structure of the character above described for the cable, 45, is shown, an eccentric, 55, being mounted in the carriage, 49, the dog, 50, being journalled on the eccentric engaging the notched flange or ratchet, 54, as described. The eccentric, 12

55, has a lever arm, 56, for rocking it, and the shoulder, 50^a, on the dog being in position to be engaged by a shoulder, 56, on the eccentric when the latter has been rocked nearly 5 180 degrees to relax the cable.

In Figs. 11 and 12 there are shown the corresponding devices for relaxing the cable, 10, consisting of the eccentric, 60, mounted on the link, 26, and having a handle, 61, for 10 rocking it, the dog, 33, being journaled on the eccentric and engaging the ratchet stem, 32, of the carriage, 30; these shoulders, 33^a, on the dog and 60^a on the eccentric being engaged for nearly 180 degrees throw of the 15 eccentric.

It will be observed from examination of Figs. 1 and 3 that the forward small wing, 15, is pivoted at a different line from the rear wing, the pivot of the rear wing being variable with the varying adjustment for height 20 while that of the forward wing is fixed, the two pivots not being parallel at any position of the pivot of the rear wing, and also that the two wings diverge at different angles 25 from the fore-and-aft line of the car. In order that the forward wing may be swung up by the swinging of the rear wing about its pivot, the rear end of the forward wing laps outside of the forward end of the rear wing, 30 and an anti-friction roller, 15^b, preferably conical, as illustrated, is interposed between the lapped ends of the two wings, being preferably mounted upon the forward wing. With this provision, the swinging of the rear 35 wing readily swings up the forward wing also.

I claim:

1. In a railway grader and spreader, in combination with a car, a spreading and leveling wing pivotally supported for swinging 40 upward and inward to withdraw it from working position, the supports to which the wing is pivoted being mounted for equal vertical movement of the wing at both ends of its operating face, and means for raising and lowering such supports.

2. In a railway grader and spreader, in combination with a car, a spreading and leveling wing which is pivotally supported for swinging upward and inward to withdraw 50 it from working position; supports to which it is pivoted mounted for equal vertical movement of the wing at both ends of its working face; means for raising and lowering such supports, and means for securing them 55 in adjusted position.

3. In a railway grader and spreader, in combination with a car, a spreading and leveling wing and supports for the same foldable for withdrawing the wing from working position to a position above the car, such supports having their inner element mounted for equal vertical movement of the wing at both ends of its driving face, and means for raising and lowering said folding supports 60 bodily with respect to the car.

4. In a railway grader and spreader, in combination with a car, a spreading and leveling wing having its operating face diverging rearwardly from the car; links extending from an upper pivotal line on the wing to a 70 fulcrum line on the car; guide tracks on the side of the car curved about an axis parallel to the link fulcrum line with a radius equal to a link length, the wing having struts terminating at a lower line parallel with the upper link pivot line and resting on said curved guide tracks, and means for swinging the links about their fulcrums to raise and lower the wing.

5. In a railway grader and spreader, in combination with a car, a spreading and leveling wing having its operating face diverging rearwardly from the car; links fulcrumed on the car and pivotally connected with the wing at an upper line; means for raising and 85 lowering the links, and struts extended from the wing having their feet terminating at a lower line; guideways on the side of the car in which said struts are footed; guide posts adjacent to the path in which the links swing, 90 and releasable means for stopping the links on the posts.

6. In a railway grader and spreader, in combination with a car, a spreading and leveling wing having its operating face diverging rearwardly from the car; links fulcrumed on the car and pivotally connected with the wing at an upper line; means for raising and lowering the links, and struts extended from the wing having their feet terminating at a 100 lower line; guideways on the side of the car in which said struts are footed; guide posts adjacent to the path in which the links swing, said posts having pin-holes at intervals and removable pins in said holes for securing the links at adjusted position.

7. A railway grader and spreader comprising, in combination with a car, a spreading and leveling wing pivotally supported on the car and having its operating face diverging 110 rearwardly from the car at working position; means for raising and lowering such wing, and means for controlling its movement to equalize the vertical components of such movement at two points of the length of its 115 said diverging operating face.

8. A railway grader and spreader comprising, in combination with a car, a spreading and leveling wing; means for raising and lowering such wing comprising a cable connected with the wing; a sheave or drum on which the cable is wound; a second sheave or drum on the same shaft; cables secured thereto and wound thereby, and a motor connected to the cable for drawing 120 thereon.

9. A railway grader and spreader comprising, in combination with a car, a spreading and leveling wing on each side of the car; a sheave or drum and a shaft on which it is 130

fixed; cables extending around the sheave and secured thereto for rotating it in opposite directions; motors connected with the cables respectively for drawing them from the 5 sheave to rotate the shaft; means connected with the respective wings for lifting them respectively by rotation of the shaft in opposite directions, the cables having each slack equal to the draft of the motor thereon for 10 lifting the wings, and take-up devices for controlling such slack.

10. A railway grader and spreader comprising, in combination with a car, a spreading and leveling wing on each side of the car; 15 a sheave or drum and a shaft on which it is fixed; cables extending around the sheave and secured thereto for rotating it in opposite directions by unwinding therefrom; motors connected with the cables respectively 20 for drawing them from the sheave to rotate the shaft; means connected with the wings for lifting them respectively by the rotation of the shaft in opposite directions, the cables each having slack equal to the draft of the 25 motor thereon in lifting the wings; take-up devices for controlling such slack, and means for locking the take-up devices to retain the slack drawn.

11. A railway grader and spreader comprising, in combination with a car, a spreading and leveling wing on each side of the car; a sheave or drum and a shaft on which it is fixed; cables extending around the sheave and secured thereto for rotating it in opposite directions by unwinding therefrom; motors connected with the cables respectively for drawing them from the sheave to rotate the shaft; means connected with the wings for lifting them respectively by rotation of the 35 shaft in opposite directions, each cable having slack equal to the draft of the motor thereon in lifting the wings; a take-up pulley for each cable and a carriage on which it is mounted for rotation, such carriage being 40 mounted for movement in direction to deflect a loop or fold of the slack of the cable; a spring operating on the carriage for drawing such slack; a ratchet and dog engaging the same for retaining the carriage in the position 45 to which it is drawn by the spring, the pivot bearing of the dog being mounted for movement to retract the dog independently of its disengagement from the ratchet, and means for so moving said bearing at will.

50. 12. In a railway grader and spreader, in combination with a car, a spreading and leveling wing on each side of the car; cables for lifting the wings; means for taking up slack in the cables comprising a pulley and a carriage for the same mounted for movement to draw the slack; a ratchet and dog device for retaining the slack, the bearing of the dog being mounted eccentrically, and means for 55 gaging it to retract the dog without disengaging it from the ratchet.

13. A railway grader and spreader comprising, in combination with a car, a spreading and leveling wing on each side of the car; a shaft and means for rotating it in opposite directions; a sheave or drum on the shaft and cables from the wings respectively extending in opposite directions around the sheave and secured thereto. 70

14. A railway grader comprising, in combination with a car, a spreading and leveling wing on each side of the car; means for raising and lowering the wings comprising a sheave or drum mounted on the car; cables from the wings respectively extending in opposite directions around the sheave or drum 80 and secured thereto; means for rotating the drum at will in either direction, each cable being provided with slack equal to the amount necessarily drawn for lifting the wing; means for taking up such slack automatically when it is yielded, and means for releasably locking the take-up device to retain the slack drawn. 85

15. A railway grader and spreader comprising, in combination with a car, a spreading and leveling wing on each side of the car; means for raising and lowering the wings comprising a sheave or drum on the car; cables from the wings respectively extending around the sheave or drum and secured thereto, the cables being provided with slack equal to the amount necessarily drawn in lifting the wing; a device for taking up the slack comprising a pulley engaging the cable and a carriage for the same mounted for movement 90 to draw the slack of the cable; a spring operating on the carriage for such slack-drawing movement; a ratchet and a dog engaging the same for retaining the carriage in the position to which it is drawn by the spring, the pivot bearing of the dog being mounted for movement to retract the dog without disengaging it from the ratchet, and means for so moving said bearing at will. 95

16. In a railway grader and spreader, in combination with a car, a spreading and leveling wing at each side of the car; means for raising and lowering the wings comprising a sheave or drum mounted on the car; cables connected with the wings respectively extending in opposite directions around the drum and secured thereto; means for rotating the drum at will in either direction consisting of another sheave or drum rigid with the first; cables extending thereabout and secured thereto for rotating it in opposite directions by unwinding therefrom; motors connected with the cables respectively for drawing them from the sheave to so rotate it, the cables connected with the wings having slack equal to the amount drawn for lifting the wing, the cables connected with the motor having slack equal to the draft of the motor thereon for lifting the wing; separate take-up devices for controlling the slack in 100 105 110 115 120 125 130

the several cables, and means for releasably locking such take-up devices to retain the slack drawn.

17. In a railway grader and spreader, in combination with a car, a wing at each side thereof; means for raising and lowering the wings comprising a sheave or drum mounted on the car; a link pivotally supported at one end on the car and pivotally connected at the other end to the wing for swinging up and down to raise and lower the wings; cables connected to the links respectively and extending in opposite directions around the drum and secured thereto; means for rotating the sheave or drum at will in either direction, each cable having slack equal to the amount necessarily drawn in lifting the wing; means for taking up such slack consisting of a pulley engaging the cable; a carriage for the pulley mounted for reciprocating on the link; a cable guide on the link between which and the attachment of the cable to the link the take-up pulley engages the cable; a spring for reciprocating the carriage to draw the slack of the cable, and a releasable locking device to retain the carriage at the position on the link to which it is thus drawn.

18. In a railway grader and spreader, in combination with a car, a spreading and leveling wing on each side of the car; means for raising and lowering the wings comprising a sheave or drum mounted on the car; cables connected with the wings respectively and extending in opposite directions around such drum or sheave and secured thereto; means for rotating the drum at will in either direction, the cable of each having slack equal to the amount necessarily drawn for lifting the wing; take-up devices for controlling such slack and means for releasably locking such devices to retain the slack; swinging links by which the wings are connected with the car, the cables being connected to the wings by attachment to the links, and the take-up devices being mounted on the links.

19. A railway grader comprising, in combination with a car, leveling and spreading wings mounted at the sides thereof having their spreading faces diverging rearwardly; supports to which the wings are pivoted at an elevated point; struts or braces extending from the lower part of the wings; footings mounted at the sides of the car for the struts or braces, and means for swinging the wings about their elevated pivotal supports to fold them back above the car.

20. A railway grader comprising, in combination with a car, leveling and spreading wings pivotally mounted at the sides thereof for swinging upward and inward out of operative position, such wings being adapted to swing inward far enough to be overbalanced inward; supports on the car against which they lean when thus overbalanced; means for raising the wings and controlling their

descent, and means for starting them outward from the supports against which they lean consisting of power cylinders having their pistons operating transversely with respect to the car in position for thrusting their stems outwardly against the wings.

21. A railway grader comprising, in combination with a car, a spreading and leveling wing having its vertical face diverging rearwardly from the car; supports to which such wing is pivoted at an elevated point; struts or braces extending from the wing toward the car below the pivots; guide-ways on the side of the car in which such struts or braces are footed; a cable connected with the wing; an elevated sheave or drum on the car about which the cable is wound, and a pivoted outrigger for the cable extending outward from the pivotal support of the wing.

22. A railway grader comprising, in combination with a car, means for spreading and leveling the spoil consisting of a forward and a rear wing, both extending off divergently from the side of the car; means for pivotally supporting both wings on the car at different pivotal lines; means for folding the rear wing upward and inward about its pivotal supports, the forward wing having its rear end lapped outside the rear wing; a roller on one of said wings bearing upon the surface of the other wing for communicating folding movement of the rear wing to the forward wing.

23. A railway grader comprising, in combination with a car, means for spreading and leveling the spoil consisting of a forward and a rear wing, both extending off from the side of the car and both diverging rearwardly from the car, the rear wing having greater angle of divergence than the forward wing; means for pivotally supporting both wings on the car; means for folding the rear wing upward and inward about its pivotal supports, the forward wing having its rear end lapped outside the rear wing; a roller on one of said wings and a shoe on the other with which the roller engages for communicating the folding movement of the rear wing to the forward wing.

24. A railway grader comprising, in combination with a car, means for spreading and leveling the spoil consisting of a forward and a rear wing, both extending off from the side of the car and both diverging rearwardly from the car, the rear wing having greater angle of divergence than the forward wing; means for pivotally supporting both wings on the car; means for folding the rear wing upward and inward about its pivotal supports, the rear end of the forward wing being lapped outside the forward end of the rear wing; a roller mounted on the inner side of the forward wing and a shoe or cam on the outer side of the forward end of the rear wing co-operating with the roller for folding up

the forward wing by the folding up of the rear wing.

25. A railway grader comprising, in combination with a car, a spreading and leveling wing extended off from the side of the car diverging therefrom rearwardly; means operating by connection with the wing at an elevated line thereon for raising and lowering it; struts or braces extended from a lower point on the wing inward and rearward to the car, and guideway pockets in which the inner rear ends of said struts are stepped, such pockets being positioned and formed to resist both rearward and inward thrusts of the struts.

26. A railway grader comprising, in combination with a car, a wing extending off sideward therefrom and diverging rearwardly from the car; means connected with elevated points on the wing for supporting the same and for guiding it in vertical movement; struts or braces extending from lower points on the wing inward and rearward to the car; pockets on the side of the car in which said struts are footed, positioned and formed for resisting both rearward and inward thrust of the struts and extended vertically to seat and guide the struts in the vertical movement of the wing.

27. A railway grader comprising in combination with a car, a wing extended off sideward therefrom; links connecting the wing at elevated points on the latter with the car; means for swinging the links about their fulcrums on the car to raise and lower the wing; struts or braces extended from lower points on the wing inward for bracing against the

car, and tracks or guideways on the side of the car against which such struts or braces are folded extending vertically curved convexly outward about centers spaced downward from the pivots of the links a distance equal to the distance between the connection of the links to the wings and the lower ends of the struts respectively, with a radius equal to the length of the links from pivot to pivot.

28. A railway grader comprising, in combination with a car, a wing extended off sideward therefrom and diverging rearwardly; links connecting the wing at elevated points on the latter with the car, and means for swinging the links about their fulcrums on the car to raise and lower the wing; struts or braces extended from lower points on the wing inward and rearward to the car; pockets on the car in which the rear inner ends of the struts are footed, positioned and formed for resisting both the inward and the rearward thrust of the struts, such pockets being extended vertically in curves about centers spaced from the pivots of the links a distance equal to the distance from the pivotal connection of the links to the wings and with a radius equal to the length between centers of links.

In testimony whereof, I have hereunto set my hand, in the presence of two witnesses, at Chicago, Illinois, this 27th day of December, 1906.

ORVILLE C. MANN.

In the presence of—

CHAS. S. BURTON,
J. S. ABBOTT.
